UNITED STATES PATENT OFFICE.

JOHN G. SODERBERG, GEORGE D. LOCKWOOD, AND WILLIAM W. ROBERTSON, OF WORCESTER, MASSACHUSETTS, ASSIGNORS TO CROMPTON & KNOWLES LOOM WORKS, A CORPORATION OF MASSACHUSETTS.

TUBE FRAME FOR AXMINSTER LOOMS.

Application filed August 21, 1922. Serial No. 583,137.

This invention relates to a tube frame particularly designed for use in looms for weaving Axminster carpet and other similar fabrics.

- 5 It is the general object of our invention to provide improved features of construction in such tube frames by which they are better adapted to the conditions under which they are used.
- 10 With this general object in view, one feature of our invention relates to the provision of an improved hanger or supporting end for a tube frame, so constructed that a larger and stronger spool bearing is made 15 possible.

Further features of our invention relate to the provision of improved means for securing the hanger springs in position to an improved spool friction device on the tube frame, and to certain arrangements and combinations of parts which will be herein-after described and more particularly pointed out in the appended claims.

A preferred form of the invention is 25 shown in the drawings in which

Fig. 1 is a side elevation of a portion of a tube frame embodying our improvements;

Fig. 2 is a side elevation of one of the hangers;

30 Fig. 3 is a right hand end elevation thereof looking in the direction of the arrow 3 in Fig. 2;

Fig. 4 is a sectional elevation, taken along the line 4—4 in Fig. 3;

35 Fig. 5 is a perspective view of a spring clip used upon our improved hanger;

Fig. 6 is a plan view of the hanger shown in Fig. 2;

40 Fig. 7 is a left hand end elevation of the hanger, looking in the direction of the arrow 7 in Fig. 2, and

Figs. 8 and 9 are plan and side views of our improved spool friction.

Referring to the drawings, we have shown 45 portions of a yarn spool 10 having heads 11 and gudgeons 12 upon which the spool is rotatably supported. The tube frame 13 is provided with hangers at each end, each hanger preferably comprising a substantially L-shaped outer member 14 and an L-shaped inner member 15.

A hanger spring 16 extends through an opening 17 (Fig. 4) in the offset upper end,

as is usual, for attaching the tube frame to the conveying chains. The lower end of the 55 spring 16 is received and held in an opening 19 in the member 14 and is secured in position on said member by a screw or rivet 20. The spring 16 is thus securely held 60 against displacement and may be so shaped initially that it will be under considerable tension when drawn to the position indicated in Fig. 4.

The upper end 21 of the inner hanger member 15 provides an open bearing for the 65 gudgeon 12. It has been heretofore customary to utilize the stock displaced in forming the opening 17 as a bearing for the spool gudgeon. With this construction, however, 70 the stock for the bearing 21 and also for the offset portion of the hanger member 14 is much limited and has been found insufficient to support the long and heavy tube frame now used. With our improved construction, the width of the bearing portion 21 75 may substantially exceed the width of the opening 17 in the member 14, as is clearly shown by a comparison of Fig. 3 with Fig. 7.

The offset lower ends of the members 14 80 and 15 extend within the tube frame 13 and engage the top and bottom thereof. A spring clip 22 (Fig. 5) is secured to the upper end of the inner bearing member 15. The clip 22 has an opening 23 through which the bearing 85 portion 21 extends and a portion of the stock from this opening is first bent forward to form a slightly inclined guide for the end of the gudgeon and is thereafter bent outward as indicated at 24 to form a shoulder 90 engaging the upper side of the gudgeon 12. Above the opening 23 the clip 22 is also recessed as indicated at 25 to assist in guiding and centering the spool gudgeon as a 95 spool is inserted in the tube frame.

We have also provided an improved friction device for the spool 10 which device preferably comprises a plate 26 of flat resilient metal having an offset portion 27 in which a block 28 of rubber or other friction material is secured. The parts are so proportioned that the face or outer bearing surface of the block 28 is approximately in alignment with the upper surface of the plate 26. This construction permits the 100 spool to be slid along over the spring 26 105

to the position shown in Fig. 1, without abruptly engaging and displacing the friction block 28, as has frequently happened when the block is mounted on a continuous flat surface of the friction spring. Easy entrance of the spool may also be facilitated by providing the friction block 28 with a beveled edge 29, as indicated in Fig. 9.

Having thus described the several features 10 of our invention, we do not wish to be limited to the details herein disclosed otherwise than as set forth in the claims, but what we claim is:—

1. In a yarn tube frame, a hanger comprising an outer supporting member and an inner bearing member permanently secured together, and a spring clip, said clip having a recessed portion adapted to guide and position a spool gudgeon in said bearing member.

2. In a tube frame hanger, a spool bearing member, and a resilient spring clip mounted thereon, said clip having a recessed portion adapted to guide a spool gudgeon to said bearing member, and having an opening in said clip for said gudgeon.

3. In a tube frame hanger, a spool bearing member, and a resilient spring clip mounted thereon, said clip having a recessed portion adapted to guide a spool gudgeon to said bearing member, and having an opening in said clip for said gudgeon, and having a

shoulder forming the outer side of the bearing for said spool gudgeon.

4. A spring clip for a tube frame hanger 35 formed from a single piece of thin resilient metal and having an attaching portion, and a recessed portion adapted to guide a spool gudgeon to its bearing position.

5. In a yarn tube frame having an end 40 bracket supporting a spool bearing, a spool tension spring comprising a strip of resilient flat metal extending longitudinally of the tube frame and having an end portion thereof remote from said bracket secured to said 45 tube frame, the free end of said spring extending from said point of attachment in an upwardly inclined direction toward said bracket and having its end portion downwardly offset, and having a block of friction 50 material disposed in said offset portion with its outer surface in approximate alignment with the upper surface of the body of said spring, whereby said block of friction material is protected from accidental engagement and displacement by a spool head during the longitudinal movement of a spool 55 relative to said tube frame while being assembled therewith.

In testimony whereof we have hereunto 60 affixed our signatures.

JOHN G. SODERBERG.
GEORGE D. LOCKWOOD.
WILLIAM W. ROBERTSON.
